UNITED STATES PATENT OFFICE.

OTTO A. LEHMAN, OF HOBOKEN, NEW JERSEY.

BELT-SLIDE.

SPECIFICATION forming part of Letters Patent No. 619,492, dated February 14, 1899.

Application filed August 11, 1898. Serial No. 688,361. (No model.)

To all whom it may concern:

Be it known that I, OTTO A. LEHMAN, a citizen of the United States, and a resident of Hoboken, in the county of Hudson and State of New Jersey, have invented a new and useful Improvement in Belt-Slides, of which the following is a specification.

My invention relates to an improvement in belt-slides in which provision is made for detachably securing the slide to the skirt to support the skirt at its back.

The object is to provide a simple and effective device for uniting the ends of the flexible strip which forms the body of the slide and at the same time prevent the slide from collapsing under the weight of the skirt, securing the pin firmly in its socket and housing the socket.

In the accompanying drawings, Figure 1 is a view of the belt-slide as it appears in use, the view being taken from that side of the belt which is placed next to the body of the wearer. Fig. 2 is a transverse section through the same. Fig. 3 is a front view of the fastening-plate with pin in position, and Fig. 4 is a rear view of the same.

The strip of flexible material—leather for example—which is to form the body of the slide is denoted by A. It may be of any suitable width and thickness. The sheet-metal plate which performs the various functions of securing the ends of the strip A, holding the slide extended, and retaining the pin is denoted as a whole by B. Its length is intended to be substantially the width of the belt C, on which the slide is to be mounted, and its width is preferably about the width of the strip A.

Across the middle portion of the plate a half-socket b is formed by forcing the body of the plate laterally, and the socket is completed for holding the shield-pin D therein by partially severing tongues b' from the body of the plate B adjacent to the half-socket b and bending them over one part of the pin D, as clearly shown in the drawings.

Broad tongues b', preferably having their free ends rounded, are partially severed from the body of the plate B upon opposite sides of

the pin-retaining socket for the purpose of 50 securing the ends of the strip A to the plate, as follows: The strip A is of such length that its ends when folded over toward each other on the side of the belt toward the body of the wearer and drawn together to loosely embrace the belt C will rest in proximity to the opposite sides of the half-socket b. At a distance back from the ends corresponding to the bases of the tongues b' the strip A is provided with transverse slits a, through which 55 the tongues b' are extended and there turned down flatly on the face of the strip A, thereby securing the ends of the strip firmly and at the same time housing the half-socket b between the ends of the strip and even with 60 or below the exposed faces of the strip. As the plate B extends along back of the fastened ends of the strip A a distance corresponding to the width of the belt, it serves 65 to hold the slide extended and prevents it 70 and the belt from collapsing under the strain of the weight attached to the pin.

By the above-described structure and arrangement of parts I make a single plate of thin sheet metal serve the several functions 75 enumerated, and the slide as a whole is light, strong, and neat in appearance, presenting no objectionable thickness or projections to interfere with the comfort of the wearer.

What I claim as my invention is— 80

The belt-slide comprising the body-strip of flexible material for embracing the belt, a plate located behind the ends of the body-strip and provided with means for holding the ends of the body-strip fast on it, the said 85 plate being further provided with a lateral bend forming a half-socket and a safety-pin having one of its branches engaged in the said half-socket, substantially as set forth.

In testimony that I claim the foregoing as 90 my invention I have signed my name, in presence of two witnesses, this 4th day of August, 1898.

OTTO A. LEHMAN.
